WINDOW FAN ASSEMBLY WITH WIDTH-ADJUSTMENT PROVISION

George A. Delf, Creve Cour, and Robert E. Kortum, Robertson, Mo.

Application December 16, 1949, Serial No. 133,392

5 Claims. (Cl. 98—94)

1

This invention relates to improvements in window fan assemblies with width-adjustment provisions, and more particularly to a simplified, positively-acting provision for shifting laterally of a fan supporting frame, one or more side panels or wing elements adjustably connected to or forming a part of the fan frame, whereby to extend the fan assembly across the window opening.

The applicants are well aware that numerous attempts have heretofore been made to attain a simplified yet positive assembly either as a part of, or as accessory to window fan assemblies, for the purpose noted. However, those thus far offered to the trade for such purpose present one or several of the shortcomings of excessive costs, unwarranted complication, or the necessity for skill in effecting proper width adjustments, to mention but a few such heretofore prevailing difficulties. It is accordingly a major and general objective of the present improvements to simplify and to render foolproof, a window fan assembly embodying width-adjusting provisions so as to enable same quickly and readily to be brought to a width such that the assembly fully bridges the window opening.

Attention is directed to a copending application on somewhat similar subject matter, filed concurrently herewith by George A. Delf and Glenn A. Delf, entitled "Variable-Width Window Fan Assemblies," and bearing Serial No. 133,391 and filing date of December 16, 1949.

The present invention may be summarized by reference to the selected disclosed embodiment thereof, as including in a complete and operative assembly, a window fan and driving motor together with a supporting frame which will usually but not necessarily consist of a housing or casing about the fan and motor, together with one or more horizontally adjustable, normally vertically disposed panel or wing elements slidably connected to the frame, and a simplified double-arm device, the elements of which are operatively connected to the one or more adjustable wings, and with which is provided a simple form of clamping means for maintaining the arms clamped in aligned relation following the desired width adjustment.

A further important advantage and object of the present improvements is realized in the provision of a pair of variably telescoping arm elements provided with a novel screw and eye type of clamp serving to maintain the adjusted relation of the panel or wing elements of the housing as well as the arms, against casual wing extending or retracting movements, and at the same

2

time providing assurance against any loosening effects due to vibration of the fan motor assembly.

Yet another important object of the invention is attained in a device of the general nature above noted and which may be formed for the most part of stock materials, with but a minimum of forming operations, and with a minimum of tooling expenditure.

10 The foregoing and numerous other objectives and advantages of the invention will more clearly appear from the following detailed description of a currently preferred embodiment, particularly when considered in connection with the accompanying drawing, in which:

Fig. 1 is a rear view of an adjustable width window fan assembly embodying the present improvements, and showing the sections of an adjustable distance arm and the slidable wing elements in adjusted position;

Fig. 2 is a fragmentary, enlarged, side elevational view of the connected arms and securing members of the width-adjustment assembly;

25 Fig. 3 is a sectional view taken along line 3—3 of Fig. 2, and

Fig. 4 is a sectional view as taken along line 4—4 of Fig. 2.

Referring now by characters of reference to the drawing, those parts of the assembly which are or may be of conventional construction include a propeller or fan of rotary type, and indicated at P, for which a driving motor M is provided, the latter being supported by hangers (not shown), in any suitable manner from the frame or housing generally indicated at FH. A planar rear wall element W of the housing proper is provided with a circular opening WO and a fan guard FG is provided either or both forwardly and rearwardly of the fan P, as desired.

30 The vertical wall element W or other frame member usually formed of sheet steel or the like, is provided with a channel formation C along its upper horizontal margin and a companion such channel C1 along its lower margin.

As will be well understood, the housing, casing or frame such as FH, is usually provided as constructed of fixed dimensions, and over a minimum width such as to occupy the smaller sizes 35 of windows generally encountered by the trade, and for the purpose of enabling the fan assembly fully to bridge the window opening as between the vertical pulley stiles or other side frame elements of the window structure, there is provided 40 one, or usually a pair of extensible and retractible

side panels or wing elements, a pair of which are indicated respectively at the left as W1, and indicated as W2 on the right (Fig. 1). Each of the wings is provided with a right angular flange WF along its free vertical margin, and similar such flanges WG at the bottom and WH along its top horizontal margin. These flanges are so proportioned as to be guidedly movable within the channel flanges C and CI incident to width adjustment of the assembly.

It is assumed for brevity of description that a single adjustment assembly will adequately serve the purpose of extending and retracting the wings W1 and W2, although in larger sizes a plurality thereof may be employed. A single such assembly as shown, consists of a channelled arm or arm section, generally indicated at 20 and connected for example to the wing W1, together with a companion such arm 21 connected to the opposite wing W2. Spot-welding zones or rivets such as 22, serve fixedly to connect each arm to the vertical midpoint of the inner marginal part of the adjacent panel or wing. Although the arms 20 and 21 may be secured in any of a number of ways to the wings or side panels W1 and W2, a fixed or rigid connection thereof in the zones 22, is entirely adequate, inasmuch as the length adjustment of the arms or sections 21, 22 may be effected without necessarily changing their relative angularity. The flexibility of the side panels or wings is such as readily to permit an out-of-line deflection of the elements 20 and 21, sufficiently to effect a disengagement thereof when desired for any purpose.

The preference for use of an arm 20 of channelled section together with a material of flat bar stock, for the arm 21, arises from the guided interfitting relation of the arm ends which, with the parts in place, acts to maintain the two arms in rigid alignment. The section of the channel of arm 20 is such as slidably to receive the bar of arm 21 with not much more than a reasonable working clearance to assure an easy sliding action of the bar within the channel, incident to adjustment.

Further for the purpose of maintaining the arms in a fixed and predetermined adjusted setting, incident to variation of the combined length of the arms or sections 20, 21, there is provided adjacent the end of the channel arm 20, a clip or ring 23 the shape of the aperture of which conforms closely to the external dimensions and shape of the arm 20. The clip 23 may be either welded in place at the end of arm 20, or frictionally retained in place thereon, so as to be susceptible of a reasonable limited range of sliding movement of the clip over the end portion of the adjacent arm. The sides of the clip 23 are formed to extend upwardly of the body and clip, and may be welded together to constitute an upward projection 24 (Fig. 2) this projection being formed to present a screw seat or face 25, presented at an acute angle to the axis of the arms, and, as will later appear, serving as an abutment for a clamp screw to be described. The abutment 25 is shown as generally circular in outline and somewhat larger in diameter than of the end of clamp screw, and may if desired be made slightly concave so as to provide a centering effect on the end of the clamp screw as the latter is threaded up.

A companion and coacting clip carried by the bar 21, is indicated at 26. The clip 26 may be formed of a flat strip stock, and its lower or body portion is provided with an eye 27 of a generally

rectangular form, and of a width to permit passage therethrough of the flat arm or bar 21, with not much more than a working clearance between the side faces of the bar and the side margins of the slot. In length, the slotted eye 27 slightly exceeds the width or vertical dimension of the bar 21, so that when the clip 26 is released, it may be slidably moved along the bar, and yet is permitted and normally assumes a slightly cocked or cramped position on the bar 21 when the elements of this clamp are in place and in locking relation to the arms attached to the side panels W1 and W2.

The aforesaid cocked position of the apertured clip 26 on the bar 21 is determined in part by the angle to the body of the member 21, of an extension 30 prolonged upwardly of the body of the clip, and normally lying at an acute angle to the axis of the arms. The extension, indicated at 30, is provided with a transverse tapped aperture for the reception of a clamp screw exemplified in the wing screw 31, the end of which, as will now appear, centrally abuts the screw seat 25 on the clip 23 above described.

The manner of effecting lateral adjustment of the one or more wing or panel elements of the present assembly together with the sections of the distance piece comprised of the two arms 20 and 21, is now thought to have been rendered apparent from the earlier description herein of the several parts, but, it may be noted that the usual installation practice in smaller or moderate size fan assemblies will consist of lifting the window sash somewhat above a height to permit resting the fan assembly on the sill or other horizontal frame member within the window opening, and laterally centered between the pulley stiles or other lateral framing elements of the window structure. The clamp screw 31 will now be released, after which the interfitted end of the arms 20 and 21 are free to be moved along their axis. The panels or wings, initially retracted, are now each extended so as to bring the one or pair thereof into snug abutment with the pulley stiles or other side elements of the window frame. Assuming now that the clip 23 on arm 20 either remains in or is brought to the position substantially as shown by Fig. 2, the wing screw 31 is rotated to assure that a substantial portion of its threaded shank falls to the right (Fig. 2) of the extension 30, so as to permit an adequate subsequent threading-up action of the screw. With the parts thus conditioned and positioned, the clip 26 is moved as far to the left on bar 21, as is permitted by the current screw setting, then is cocked as far to the right (Fig. 2) as permitted by the augmented length of the slot or eye 27, and while held in such position the wing screw 31 is threaded tightly against the screw seat 25. In case clip 23 is not secured fixedly to the end of the channelled arm 20, it will appear that the clip 23 similar to clip 26, will also assume a slightly cocked and frictionally-retained relation to the end of the channelled arm.

With the parts thus related they are clampingly yet releasably retained in an adjusted width position. It will of course be impossible, since the panels or wings abut the stiles along their lateral margins, for the arms or wings to be further extended in a horizontal direction. Similarly, due to the firm abutment of the end of the wing screw upon the seat 25, it is now impossible for the arms to be further telescoped at least until the screw is later released. To the extent possible, it is desirable that the extending action

on the wings and arms be manually effected so as, if possible, to locate the parts under a condition of slight compression, for maximum assurance against undesired vibration effects, and to obviate loosening effects on the parts which might otherwise occur after a considerable period of operation of the fan and motor.

It will now have appeared that the assembly as described will serve fully to attain each of the objectives hereinabove expressed as well as numerous others implied from the later description. Although the invention has been described by detailed reference to a single embodiment, the detail of description should be understood as instructive rather than in any limiting sense, inasmuch as numerous variants are possible within the intended scope of the claim hereunto appended.

We claim as our invention:

1. In an adjustable width window fan assembly, a fan, a driving motor therefor, a frame structure supporting the fan and motor, a pair of longitudinally slidable wing elements located one at each opposite side of said frame structure, an arm attached to each of said wing elements, one of said arms being of a channelled section and the other said arm consisting of a bar adapted closely to interfit the channelled arm, a slotted member slidable along said bar, the slot therein being of appreciably greater length than the width of said bar, whereby the slotted member may be clamped or cocked in place on the bar, a threaded element carried by the slotted member and normally disposed at an acute angle thereto, and an abutment for the threaded element carried by the channelled arm, with the abutment surface thereon at an acute angle to the axis of said channelled member.

2. In a window fan assembly, a casing for insertion in the window opening, a fan and motor in said casing, a wing at one side of said casing, means providing for slidable horizontal movement of the wing member in guided relation to the casing, whereby to provide for a variable width of the casing assembly, a pair of distance arms for adjusting the setting of said wing, one such arm being attached to said wing, the other said arm being attached to a laterally opposite portion of the assembly, one of said arms consisting of a rigid bar, the other said arm consisting of a rigid element provided with a longitudinal channel to receive in telescoping relation a variable portion of the bar, an eye member on the first said arm having an opening through which the said bar arm extends, which opening is of a sectional area in excess of that of the bar whereby the eye element may be cocked on the bar in a position for its frictional retention thereby, a screw on the eye element extended at an acute angle to the bar arm by which it is carried, the opposite said arm being provided with an acute angled abutment located for engagement by said screw, whereby the eye element, screw and abutment coact as a clamp structure for limiting the telescoping relation of said arms and thereby establishing the adjusting position of said wing with respect to the casing.

3. The combination in a window fan assembly including a propeller, a motor therefor, a frame of fixed dimensions supporting the fan and motor, and adjustable wings one at each side of the frame and slidably connected thereto for width adjustment of the assembly, a horizontal arm attached to each of said wings, the arms be-

ing respectively of such section that one may telescopically interfit the other, a slide loosely embracing one of said arms, and including a projection above the body of the slide and having a tapped opening therethrough, a clamp screw threadedly engaging the tapped opening and located at an acute angle to the axis of the arm by which the slide is carried, a projection on the other said arm, and extended in a direction to be engaged by said clamp screw, the clamp screw coacting with said slide and projection to cock the slide in a frictionally-retained position on the arm by which it is carried, whereby to limit the extent of telescoping interengagement of said arms.

4. In a window fan assembly, a casing of fixed dimensions, a fan and motor within the casing, a wing structure located laterally of the casing and in a slidable, guided relation thereto, means for adjusting and fixing the position of the wing structure with respect to the casing, and comprised of a pair of slidably interengaging rigid arms, a vertically slotted clip having an eye quite loosely engaging, so that the clip is rockable and slidable over one of said arms, and having an acute angled extension in its upper portion, said extension being provided with a tapped aperture, a clamp screw engaging said tapped aperture and normally located at an acute angle to the axis of the arm by which the clip is carried, a fixed clip carried by the other said arm, and provided with an upper abutment having an acute angled seat adapted for engagement by the screw on the first said clip, the clamp screw being adapted, when threaded firmly against said abutment, to cock the first said clip on the arm by which it is carried, and thus to establish an adjusted minimum combined length of said arms for the purpose of fixing the position of the wing structure with respect to the casing.

5. In a window fan casing assembly including a pair of laterally adjustable wings, means by which the wings are slidably connected to the casing, a rigid arm fixedly secured to each wing, one of said arms consisting of a flat metal bar, the other said arm consisting of a channelled member dimensioned so as to receive said bar in telescoping relation thereto, a pair of clips one carried by each of said arms, the clip on said one arm having a slotted eye portion the length of which exceeds the width of the arm by which it is carried, and having an acute angled upper projection provided with a tapped opening, a wing screw engaging said opening, the clip on the other said arm including an upper extension provided with an abutment sloped with respect to the axis of the arm by which it is carried, and adapted for engagement by the end of said clamp screw, the clamp with said clips and screw providing a limit of telescoping engagement of the arms, and thereby serving to establish a predetermined minimum spacing of the wing elements.
